ATTORNEY

UNITED STATES PATENT OFFICE.

THOMAS A. REID, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRIC CRUCIBLE FURNACE.

Application filed January 7, 1922. Serial No. 527,644.

To all whom it may concern:

Be it known that I, THOMAS A. REID, a citizen of the United States, and a resident of Wilkinsburg, in the county of Allegheny and State of Pennsylvania, have invented a new and useful Improvement in Electric Crucible Furnaces, of which the following is a specification.

My invention relates to electric furnaces and particularly to electric-resistance furnaces of the crucible type and it has for its object to provide a relatively simple, inexpensive and easily installed resistor and resistor support for an electric-resistance furnace.

In practising my invention, I provide a refractory heat-insulating casing which may be tiltably mounted and which has a substantially circular chamber located therein. I provide a plurality of relatively thin refractory plates, of arcuate form in lateral cross-section, located in abutting relation to constitute a substantially cylindrical lining for the chamber in the refractory casing. Each of the refractory plates is provided with a plurality of relatively small, spaced-apart, alined, integral projections on the convex surface, and a preformed resistor member is located in operative engagement on the convex surface and is maintained in proper operative position relatively thereto by the alined integral projections.

In the single sheet of drawings,

Figure 1 is a top plan view of an electric-resistor furnace comprising a device embodying my invention;

Fig. 2 is a view, in vertical cross-section, of a furnace of the above designated type taken on the line II—II of Fig. 1;

Fig. 3 is a view, in front elevation, of one of the refractory plates having a resistor operatively associated therewith.

A substantially cylindrical metallic casing 11, provided with a bottom plate 12, has located therein an outer lining 13 of any suitable heat-insulating material. An inner lining 14 may comprise either a plurality of bricks or blocks of a suitable refractory high-temperature-resisting material or the entire lining may be built up in integral form in any manner well known in the art. The inner lining 14 is so shaped and disposed as to provide a chamber 15 therein which may be substantially cylindrical in form.

A plurality of standards or supports 16 are provided, having bearings at their upper ends in which short shafts 17 are located, the inner ends of which are suitably secured to the metallic casing 11. A pinion 18 is suitably secured to the outer end of one of the shafts 17 to permit of tilting the entire casing by tilting mechanism (not shown) to cause the molten material to be poured from a crucible 19 located within the chamber 15. While I have illustrated the member 18 as a pinion, this may not be necessary, particularly in furnaces of relatively small size in which a hand wheel may be employed.

Within the chamber 15 are located a plurality of relatively thin refractory plates 21, of arcuate form in lateral cross-section, and, as illustrated particularly in Fig. 1 of the drawing, the arcuate extension may be substantially 90° to permit of the use of four such plates in abutting relation to constitute a refractory lining for the chamber 15. A plurality of relatively small, spaced-apart, alined integral projections 22 are provided on the outer or convex surface of each of the plates 21 and the relative dimensions of the plates 21 and of the chamber 15 are such that the outer ends of the integral projections 22 operatively engage the inner face 65 of the wall of the chamber 15.

A preformed resistor member 23 may comprise a plurality of integral end-connected convolutions substantially as illustrated in Fig. 3 of the drawing, the adjacent convolutions of the resistor member being maintained in proper operative positions relatively to each other by the alined projections. This type of refractory plate and of an associated resistor is more particularly described and claimed in a copending application, Serial No. 449,685, filed by O. A. Colby and myself on March 5, 1921, and assigned to the Westinghouse Electric & Manufacturing Company.

While the resistor member 23, as illustrated in Fig. 3, has integral convolutions extending over the external surface of only one of the refractory plates 21, I may employ a relatively longer rod or bar 23 and mount the same in substantially the position illustrated in Fig. 3 but engaging all of the members 21 to the effect that only two ends 24 need be brought out to suitable terminal blocks 25 which may be located at the bot-

tom of the casing on the plate 12 or in any other convenient location. Connection may be made to a suitable supply circuit by means of flexible cables 26, the ends of which 5 may be electrically connected to the ends 24 by means of suitable bolts 27.

The device embodying my invention thus provides a relatively simple heating element which may be quickly mounted in, and dis- 10 mounted from, its operative position in a refractory casing.

While I have illustrated a specific embodiment of my invention, I desire that only such limitations shall be placed thereon as 15 are imposed by the prior art or are specifically set forth in the appended claims.

I claim as my invention:—

1. In an electric furnace, in combination, a crucible, a plurality of relatively thin 20 refractory plates, of arcuate form in lateral cross section, having a plurality of relatively small, spaced, alined, integral projections on the outer surface thereof, a heat-insulating wall surrounding the side and bottom 25 of said crucible and an electric resistor operatively engaging the outer surface of said refractory plates and maintained in proper operative position relatively thereto by said integral projections co-operating with the 30 inner surface of said side walls.

2. In an electric furnace, in combination, a refractory casing, a plurality of relatively thin refractory plates, of arcuate form in lateral cross-section, each plate having a 35 plurality of relatively small spaced, alined, integral projections on the outer surface thereof and the said plates fitting within said casing, and a resistor member located 40 between said plates and said casing and operatively engaging said plates at their outer

surface only, the said portions thereof being maintained in proper operative position relatively to each other by the alined projections.

3. In an electric furnace, in combination, 45 a tiltably-mounted refractory heat-insulating casing, a plurality of relatively thin refractory plates, of arcuate form in lateral cross-section, the said plates being located in abutting relation, and constituting a substantially annular inner lining for said refractory casing and each plate having a plurality of relatively small, spaced, integral, alined projections on the outer arcuate surface thereof, and a resistor having return-bent portions located between said plates and an inner surface of said casing, the portions of said resistor being maintained in proper operative position by the alined projections. 50

4. In an electric furnace, in combination, 55 a tiltably-mounted refractory heat-insulating casing having a substantially cylindrical chamber therein, a plurality of relatively thin refractory plates of arcuate form in lateral cross-section, located in abutting relation in and constituting a substantially annular lining for said chamber, each plate having a plurality of relatively small spaced, alined integral projections on the outer surface operatively engaging the cylindrical walls of the chamber and a resistor member having a plurality of return bent 60 portions located between said plates and said casing wall and terminal members mounted on said casing. 65

In testimony whereof, I have hereunto 70 subscribed my name this 16th day of December, 1921.

THOMAS A. REID.
